UNITED STATES PATENT OFFICE.

JOHN HAVRAN, OF PORTLAND, OREGON.

SHADE CIRCUIT-CLOSER.

1,358,636.

Specification of Letters Patent.

Patented Nov. 9, 1920.

Application filed November 22, 1917. Serial No. 203,416.

To all whom it may concern:

Be it known that I, JOHN HAVRAN, a subject of the Emperor of Austria, residing at Portland, in the county of Multnomah and

5 State of Oregon, have invented certain new and useful Improvements in Shade Circuit-Closers, of which the following is a specification.

This invention has relation to signaling systems, and has for an object to provide 10 an electrically operable signal associated with shade roller brackets of a specific construction whereby the act of raising or lowering the shade will sound the signal thereby notifying the occupants of the house of 15 the fact, for use as a burglar alarm or for other purposes.

Another object of the invention is to provide a shade roller bracket or brackets of a 20 specific construction operable in the capacity of a circuit closer when the shade is raised or lowered for the purpose above described.

In addition to the foregoing my invention comprehends improvements in the details of 25 construction and arrangement of the parts to be hereinafter more fully described and particularly set forth in the appended claims.

In the accompanying drawings in which 30 similar and corresponding parts are designated by the same characters of reference throughout the several views in which they appear:—

Figure 1, is a view in front elevation of a 35 shade roller mounted in brackets constructed in accordance with my invention, and illustrating diagrammatically the electrical connection therebetween.

Fig. 2, is a vertical section taken through 40 one of the brackets, and

Fig. 3, is a view of the brackets shown in the preceding figure in side elevation.

With reference to the drawings, 10 indicates a shade roller having, for the purposes 45 of my invention, a metallic cap 11 at each end, said caps being electrically connected through the medium of a conductor 12 which may extend through the shade roller.

The trunnion 13 on the left hand end of 50 the shade roller may be rectangular in cross section and engaged in a complementary opening in the left hand bracket 14 whereby the spring usually provided within the roller may be held against rotation during relative 55 rotative movement of the shade roller. However, the extremity of the trunnion 13 is

provided with a laterally extending lug 15 to engage the exterior surface of the bracket 14 whereby to prevent longitudinal movement of the shade roller.

60

The trunnion 16 at the right hand end of the shade roller is formed with a cylindrical portion 17 adjacent the end of the roller, and an extension 18 of said cylindrical portion which extension 18 is flattened in cross 65 section and substantially rectangular as shown in Fig. 3. The right hand end of the shade roller is mounted in a bracket which comprises a base plate 19 for attachment to the window casing having a forward extension 20 which is formed with a central opening 21 of a diameter slightly larger than the diameter of the cylindrical portion 17 of the trunnion 16. A disk of insulating material 22 is secured to the inner 70

surface of the extension 20 of the bracket through the medium of screws 23 or the like, said disk 22 having a central opening 24 in which the cylindrical portion 17 of the trunnion 16 is snugly engaged in a manner however to permit rotation of the trunnion 75 therein. A bracket is secured to the exterior face of the extension 20 of the right hand bracket adjacent the base plate 19 thereof, said bracket consisting of a strip 25 secured to the exterior face of the extension 20 through the medium of screws 26, the lower end of the strip 25 being bent upwardly as at 27 and apertured. A spring contact finger 28 is provided having its rear end apertured whereby it may be engaged to the portion 27 of the strip 25 through the medium of a bolt 29 whereby the opposite end may extend forward to a point beneath the rectangular portion 18 of the trunnion 16 80

and urged upward by the inherent resiliency of the spring finger, said upward movement however being limited by the provision of a stud 30 extending from the extension 20 of the end bracket. It will be noted that when 100 the rectangular portion 18 of the trunnion 16 is disposed parallel to the strip 28 said trunnion and strip are out of contact, contact between the two however being readily established by rotating the shade roller so as 105 to dispose the rectangular portion 18 of the trunnion at right angles to the former position whereby one edge or the other of the rectangular portion of said trunnion may engage the contact strip 28 for a purpose 110 which will be presently apparent.

I further provide an electrically operable

audible signal secured at 31 having one terminal connected by means of a conductor 32 to the left hand bracket 14 of the shade roller. A conductor 33 is further provided 5 to connect the other terminal of the signal with the right hand bracket of the shade roller, a source of current 34 being interposed in said conductor.

It will be obvious that if the shade roller 10 is rotated by pulling down the shade, or permitting the same to move upward the trunnion 16 during rotation thereof will alternately engage opposite sides of the rectangular portion 18 with the contact strip 15 28 thereby transmitting impulses of current to the audible signal 31 to sound the same thus notifying the occupants of the house that the shade has thus been moved. If a switch is provided in the circuit the switch 20 may be retained in open position during the day which will permit free use of the shade roller without sounding the signal, however, during the night the switch may be closed so that a sounding of the signal will warn 25 the occupants of the house of an attempted entrance of an unauthorized person. The signal 31 may be either of the single stroke or vibrating type.

While I have illustrated and described my 30 invention with some degree of particularity, I realize that in practice various alterations thereover may be made, and I therefore desire to reserve the right and privilege of changing the form of the details of construction, or otherwise altering the arrangement of the correlative parts without departing from the spirit of the invention or the scope of the appended claims.

Having thus described my invention 40 what I claim as new and desire to secure by Letters Patent is:—

1. In combination, a shade roller having a trunnion rectangular in cross section, a bracket adapted to support said trunnion to 45 permit free rotation of the shade roller, and a contact finger mounted on the bracket for intermittent engagement with the rectangular trunnion during rotation of the shade roller.

50 2. In combination, a shade roller having a trunnion formed with a cylindrical portion and a portion which is angular in cross section, a bracket having a journal for the cylindrical portion of the trunnion, and a contact finger mounted on the bracket for 55 intermittent engagement with the angular portion of the trunnion during rotation of the shade roller.

3. In combination, a shade roller having 60 a trunnion formed with a cylindrical portion and portion which is angular in cross section, a bracket having an opening to receive the trunnion in spaced relation thereto, a disk of insulating material secured to the

bracket having a journal to receive the cylindrical portion of the trunnion, and a contact finger mounted on the bracket for intermittent engagement with the angular portion of the trunnion during rotation of the shade roller.

4. In combination with a curtain shade, a bracket for shade rollers having an opening to receive the trunnion, a rectangular extension extending from said trunnion, a disk of insulating material secured to the 70 bracket and having an opening in registration with the opening of the bracket and slightly smaller in diameter than said opening of the bracket, a spring contact finger adapted to extend across the opening of the 75 bracket for intermittent engagement with the said extension during rotation of the shade roller, and means for limiting vibratory movement of said finger.

5. In combination with a shade roller 85 having a trunnion with a flat side, an electrical circuit including a contact lying in the path of movement of the trunnion and adapted for wiping contact therewith when the latter is rotated, and means to normally hold the contact spaced from the flat side 90 of the trunnion.

6. In combination with a shade roller having a trunnion provided with a rectangular portion, a bracket supporting said roller, 95 means extending along the side of the bracket and beneath the rectangular portion for intermittent engagement therewith, and means for limiting the vibrating movement of the first mentioned means.

7. In combination with a shade roller, a bracket, an insulator disk secured to the bracket for supporting the roller, a spring contact finger extending along the outer face of the bracket, and means extending 100 from the roller for intermittent engagement with said finger.

8. In combination, a roller, a trunnion extending therefrom, a rectangular portion extending from the trunnion, a bracket having an opening therethrough, an insulating disk secured to the inner face of said bracket and provided with an opening for receiving and supporting said trunnion, and a spring contact finger positioned adjacent the outer face of the bracket and extending below the rectangular portion, said finger being held normally out of engagement with the rectangular portion, but capable of intermittent engagement therewith upon rotation of the roller.

In testimony whereof I affix my signature in presence of two witnesses.

JOHN HAVRAN.
